FIG. 1

FIG. 2

INVENTOR:

Abraham Sager
BY Kent W. Womell # ATTORNEY.

UNITED STATES PATENT OFFICE

136,136

DESIGN FOR A FINGER RING

Abraham Sager, Chicago, Ill.

Application February 8, 1941, Serial No. 98,849

Term of patent 14 years

To all whom it may concern:

Be it known that I, Abraham Sager, a citizen of the United States and resident of Chicago, in the county of Cook and State of Illinois, have invented a new, original, and ornamental Design for a Finger Ring, of which the following is a specification, reference being had to the accompanying drawing forming a part thereof.

In the drawing,

Fig. 1 is a perspective view of a finger ring showing my new design; and

Fig. 2 is an enlarged fragmentary plan view showing the design details.

The ornamentation shown extends throughout the entire circumference of the ring.

This design is characterized by a central outer raised rectangular rim divided by transverse notches into approximately square top surfaces each having a relatively small flat circular center and rounded outwardly flaring grooves extending radially therefrom to the edges, to represent the center and leaves of a conventional flower, and providing surfaces to radiate light simulating a gem.

I claim:

The ornamental design for a finger ring, as shown and described.

ABRAHAM SAGER.
